UNITED STATES PATENT OFFICE.

EDGAR H. CLARK, OF RICHMOND HILL, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed February 7, 1924. Serial No. 691,186.

To all whom it may concern:

Be it known that I, EDGAR H. CLARK, a citizen of the United States of America, residing at Richmond Hill, Long Island, in the county of Queens and State of New York, have invented certain new and useful Improvements in Telephone-Exchange Systems, of which the following is a full, clear, concise, and exact description.

10 This invention relates to telephone exchange systems and more especially to those systems in which automatic switches are employed for the purpose of establishing talking connections.

15 An object of the invention is to prevent interference when a line is functioning both as a calling and as a called line.

In telephone systems which make use of switches of the coordinate type it has been 20 customary to provide a master controlling mechanism in association with the line switch for the purpose of controlling the operation thereof in such a manner as to prevent interfering connections being made 25 thereby. In such systems the initiation of a call causes the master controlling mechanism to operate a pair of so-called line and trunk vertical magnets, the completion of the connection of the calling line with an

30 outgoing trunk through the line switch being under complete control of the master mechanism. In such systems the seizure of a calling line by a final connector, at any time from the moment of initiation of a 35 call until the completion thereof through the line switch is of no effect in preventing further functioning of said line switch.

A feature of the invention therefore is the means for completing a connection through 40 a line switch, of the coordinate type, directly under control of the line relay.

Another feature of the invention is the means for releasing an automatic switch which has been partially operated as a 45 result of the initiation of a call when the line initiating the call is simultaneously connected to by a final selector.

Other features and advantages inherent 50 in the invention will become apparent after a consideration of the detailed description and the appended claims.

The several figures of the drawing when arranged in the manner shown in Fig. 5 disclose a sufficient portion of a telephone

system employing coordinate switches to 55 render the object and features of the invention clear.

Fig. 1 shows a number of subscribers' lines terminating in a line switch of the coordinate type. In conjunction with this 60 line switch is shown a master controlling mechanism and a trunk allotting mechanism.

Fig. 2 shows a district trunk with associated controlling apparatus, and a schematic representation of a district selector switch. 65

Fig. 3 shows a sender selector switch also of the coordinate type, and an allotter mechanism for preselecting an idle sender. 70 In the lower right-hand corner of this figure is shown a portion of a subscriber's sender and a schematic outline of the register mechanism.

Fig. 4 to the left of and above the broken 75 line represents a group selector switch of the coordinate type. To the right of the broken line is shown a final selector switch for connecting to called subscribers' lines. Below the broken line is shown a portion 80 of the marker controlling and testing mechanism.

General description.

The line switch 100, district selector 85 switch 200, group selector switch 450, final selector switch 400 and sender selector switch 300, are all of the coordinate type, such as disclosed in the patent to J. N. Reynolds, No. 1,507,140, September 2, 1924, 90 and further shown and described in the patent to S. B. Williams, Jr., No. 1,517,331, December 2, 1924. They consist, in the main, of vertical and horizontal operating members and horizontal link circuits, the 95 operating members being controlled by corresponding actuating magnets. The magnets associated with vertical members are designated as line and trunk magnets. The operation of a line and a trunk magnet 100 in conjunction with a horizontal magnet causes an incoming line to be connected with an outgoing trunk by means of an idle link circuit.

For the purpose of better illustrating the 105 features of the invention let it be assumed that the subscriber at station 101 initiates a call. Upon removing the receiver from

the switchhook the line relay operates and it in turn initiates the operation of a master controlling mechanism in such a manner as to prevent double connections to the same link, or to the same trunk. The master mechanism functions to operate a line and a trunk vertical magnet, after which the horizontal magnet corresponding to an idle link is operated, thus completing connection 10 through switch 100. From the instant the call is initiated until the time that the horizontal magnet operates, the operation of switch 100 is under control of the line relay in such a manner that should for any 15 reason the latter be released, further functioning of the line switch in extending the calling line is impossible. Once the horizontal magnet is operated, however, the sleeve conductor of the calling line is 20 grounded thus rendering the calling line busy to all final selector switches.

In systems such as disclosed in the patent to S. B. Williams, Jr., No. 1,517,331, Dec. 2, 1924, the line relay functions as a starting 25 relay for the master controlling mechanism. As soon as the latter is started in operation the control of the line switch in extending the calling line and associating it with a 30 sender selector, and sender register mechanism is rendered independent of the line relay. Should therefore the calling line be connected to by a final selector switch during the period subsequent to the operation 35 of the line relay and prior to the operation of the horizontal magnet, the release of the line relay is of no effect in preventing further functioning of the line switch 100. Under this condition the line switch will 40 continue to operate to connect with a sender selector, which will in turn select an idle sender, even though the calling line has been meanwhile seized by a final selector switch.

From the foregoing general description it will be apparent that in such systems once 45 the horizontal magnet operates and locks to the grounded sleeve conductor of the outgoing trunk, association of the calling line with a sender selector and a sender is inevitable. However, by placing the operation 50 of the horizontal magnet under direct control of the line relay any release of the latter prior to the operation of the horizontal magnet will cause the complete release of the line switch and the prevention 55 of further outgoing selection thereby, thus preventing interference as a result of the calling line being called.

Detailed description.

60 When a calling subscriber, as the subscriber at station 101, is desirous of conversing with another subscriber, as the subscriber at station 402, the removal of the receiver completes a circuit for operating line relay 104. With the line relay operated 65

a circuit is thereupon completed for group relay 105. Relays 105, 106 and 107 form a controlling mechanism for all lines which terminate in vertical row of contacts 110. In a similar way there will be provided 70 other sets of control relays for each of the other vertical rows of line contacts. The circuit for operating relay 105 may be traced from battery through its winding, left armature and contact of relay 107, right 75 inner armature and contact of relay 104 to ground at the left armature and contact of relay 118. The operation of relay 105 completes a circuit from battery through the left winding of relay 106, left armature and front contact of relay 105, armature and back contact of relay 108, to ground through the normal contacts of relays 112 and 113. Relay 106 at its right armature and back 80 contact opens the locking circuit for all succeeding similar relays, thus preventing lines in other vertical groups gaining simultaneous access to the same link or to the same outgoing trunk. Relay 106 locks in a circuit traced from battery through its right hand winding and armature and locking contact, winding of relay 108, to ground at the armatures of relays 112 and 113. Relay 108 operates in this circuit. It will be observed that relays 108, 111, 112, and 113 constitute a controlling mechanism which is common to all sets of vertical group relays. With relays 106 and 108 operated a circuit is completed from battery through the winding of line vertical magnet 114, left middle 90 armature and contact of relay 106, armature and front contact of relay 108 to ground at the armature of relay 113.

Assuming trunk 120 to be busy, then relay 115 associated therewith is operated and a circuit is now closed from battery through the winding of trunk vertical magnet 116, lowermost armature and back contact of relay 131, lowermost armature and front contact of relay 115, left innermost contacts of relay 106 to ground through the armature and front contact of relay 108. With the line vertical magnet 114 and trunk vertical magnet 116 operated, the master switch starts to release under control of the slow operating relays 111 and 112. The circuit for operating relay 112 may be traced from ground at the lower outer armature and contact of magnet 116, lower inner armature and contact of magnet 114, to battery through the winding of relay 112. When relay 112 closes its front contacts an obvious operating circuit is completed for relay 111. During the interval that relays 111 and 112 are attracting their armatures, a circuit is completed for the horizontal magnet associated with an idle link circuit.

When relay 106 operated, a circuit was closed from battery through the right-hand 130

winding of relay 117, right armature and contact of relay 118, right armature and back contact of relay 119, right outer armature and back contact of relay 104, left outer armature and contact of relay 106, to the grounded conductor 150. Relays 117, 118 and 119 form a controlling mechanism which is individual to a group of horizontal links. Similarly relays 121, 122 and 123 form a controlling group associated with another set of links. Relay 117 in operating opens the locking circuit for all succeeding similar relays, thus preventing simultaneous seizure of links in different groups. Relay 117 also locks in a circuit traced from battery through its left winding left armature and locking contact, winding of relay 109 to ground at the armatures of relays 112 and 113. Relay 109 operates in this circuit and completes an obvious operating path for relay 119.

Assuming link 135 to be the first idle link of the group of links to which the calling line has access, a circuit is completed from battery through the right hand winding of magnet 126, right inner armature and back contact of relay 127, right inner armature and front contact of relay 125, right armature and contact of relay 117, right armature and front contact of relay 119, right outer armature and front contact of relay 104, left outer armature and contact of relay 106 to the grounded conductor 150. The operation of magnet 126 completes the connection of line 101 with trunk 128 causing the successive operation of relays 201 and 202. Relay 202 connects ground to the sleeve conductor of the trunk to provide a holding circuit for magnet 126, in series with relay 127, and to render the calling line busy by operating cutoff relay 130 which causes the release of line relay 104.

When relays 111 and 112 finally open their normal contacts, the master switch is released for use in controlling the extension of another calling line. Magnets 114 and 116 are now released. When magnet 116 releases the short circuit is removed from the winding of trunk relay 131 which operates to the grounded sleeve conductor of the trunk and transfers the starting conductor 151 to the trunk relay associated with the next idle trunk. The connection through switch 100 is maintained by the continued energization of magnet 126 which is locked in series with relay 127 to the grounded sleeve conductor. From the foregoing description it will be seen that from the time of initiating a call until the actual operation of magnet 126 the latter is under direct control of line relay 104, release of which will immediately open the energizing circuit of magnet 126.

When magnet 116 operated ground was extended over the sleeve conductor of the

trunk, through the back contact of relay 202, conductor 220 to battery through the winding of relay 301. Relay 301 functions in a similar manner to the line relay 104 and starts the process of connecting the calling line with an idle sender. The above traced operating circuit for relay 301 was broken when relay 202 operated, but a locking circuit was maintained by means of the ground at the armature of relay 203. Relays 321, 322 and 323 function in a manner similar to that described in connection with relays 105, 106 and 107, causing the operation of the corresponding vertical magnet 330. Switch 350 is of the preselector type and is normally resting upon a set of terminals corresponding to an idle sender so that when relay 324 operates in series with the right hand winding or relay 323, a circuit is closed from battery through the winding of magnet 331, brush 360 and cooperating contact, armature and contact of relay 335, right inner armature and contact of relay 327 to ground at the right inner armature and contact of relay 324. Relay 327 at its right outer armature and back contact completes an obvious circuit for the slow release relay 329 which provides a holding ground for relays 324 and 323. When relay 323 operated it connected ground through its left outer armature and contact, the right outer armature and contact of relay 301, to battery through the left winding of horizontal group relay 325. Relay 325 locks in a circuit traced from battery through its right hand winding and right armature and locking contact, winding of relay 326 to ground at the lower armature and contact of magnet 330. Magnet 331 also closes a temporary locking circuit for itself traceable from battery through its winding, lower inner armature and contact, winding of relay 327 to ground at the armature of relay 224. Relay 327 operates in this circuit as soon as switch 350 steps ahead and opens the shunt around said relay and opens the previously described circuit for maintaining relay 329. The switch 350 it will be noted is operated as soon as magnet 331 operates in an obvious circuit. While relay 329 is releasing a circuit is completed to operate the horizontal magnet associated with an idle link. Assuming link 332 to be idle, when relay 327 operates ground is connected through its right outer armature and front contact, right armature and contact of relay 326, left armature and front contact of relay 325, left armature and front contact of relay 336, left armature and back contact of relay 333, to battery through the winding of magnet 328.

When relay 329 retracts its armature the master controlling mechanism releases causing the release of vertical magnets 330 and 334. Connection through switch 300 is, how-

ever, maintained by horizontal magnet 328 which locks in series with relay 333 to the grounded conductor 340.

As soon as horizontal magnet 328 operated ground at the lower outer armature of magnet 324 was extended to conductor 340, through contacts of switch 300, conductor 353 to battery through the winding of relay 203. Relay 203 operates and connects 10 the tip and ring conductors of the calling line through contacts of sender selector switch 300 to the winding of relay 380 and the left winding of retardation coil 351. Relay 380 operates in this circuit and completes 15 an obvious operating path for relay 352. When relay 203 operates it also provides a holding circuit for relay 202 to maintain ground on the sleeve conductor of the outgoing trunk.

20 The calling subscriber now dials the designation of the wanted line, relay 380 following the impulses in the well-known manner. For the manner in which the designation of the wanted line is recorded on the registering mechanism 370, reference may be had to the patent to S. B. Williams, Jr., 1,517,331, Dec. 2, 1924. When the thousands digit has been recorded the district switch 200 is operated in such a manner as to cause the calling line to be connected with a trunk leading to the proper group selector switch as 25 450. For a description of the manner in which the latter selection takes place, reference may be had to the above mentioned 30 patent of S. B. Williams, Jr.

35 The record of the hundreds, tens and units digits is now transferred to a marker controlling mechanism for the purpose of operating a pair of group selector vertical magnets as magnets 410 and 411. A test is then made of the several trunks leading 40 from the group selector 450 to those final selector switches which have access to the called line. A test is also made of the group 45 magnets as magnets 410 and 411, and of how the links in switch 450 to which the outgoing trunks have access. For a detailed description 50 of how the record of the called line is transferred to the marker mechanism to thereby cause the operation of the group 55 selector magnets 410 and 411, and of how the cross-point tests are made reference may be had to the above cited patent to S. B. Williams, Jr.

60 When group selector vertical magnet 411 operates it causes the operation of marker relay 412 which is slow to release. With relay 412 operated marker controlling ground is extended through its front contact, armature and back contact of relay 413 to battery through the winding of relay 414. Relay 414 operates and extends the above 65 traced ground through its inner armature and contact to battery through the winding of relay 422. At this time also a circuit is completed 70 from battery through the wind-

ing of final selector vertical magnet 420, armature and contact of relay 412 to the marker holding ground. The operation of magnet completes an obvious circuit for relay 413. With relay 413 operated a circuit 75 is closed from battery through the winding of horizontal test magnet 415, armature and front contact of relay 413 to ground through the armature and front contact of relay 412.

80 The line marker now functions in the manner described in the above mentioned patent to S. B. Williams, Jr., to operate the proper one of the vertical magnets such as 421, associated with the vertical row of contacts in which the called line appears. When relay 413 operated it opened the holding circuit for slow relay 414 which released, in turn opening the holding circuit for relay 422. While relay 422 is releasing a test is made of the called line and of the several 85 links in the final switch having access thereto. Assuming the called line to be busy ground on the sleeve conductor thereof is extended through the test link and contacts of switch 400, left outer armature and contact of relay 414, left armature and contact of relay 422, to battery through the winding of relay 416. Relay 416 operates and locks to the marker holding ground. The operation of relay 416 also opens the previously 90 prepared operating circuits of group selector horizontal magnet 430 and final selector horizontal magnet 440, thus preventing connection with the called line.

95 Should, however, the called line be idle 100 or in the process of being connected through a line switch as a result of a call being initiated thereon, no ground will be found on the sleeve conductor when magnet 415 operates thus allowing relay 416 to remain normal. When, therefore, relay 422 releases, marker holding ground is connected through the right armature and back contact of relay 422, left armature and contact of relay 416 to battery through the left windings 110 of magnets 430 and 440 in parallel. As soon as horizontal magnets 430 and 440 operate the sender and marker are released as described in the above mentioned patent to 115 S. B. Williams, Jr. Relay 203 having been deenergized when the sender selector was released, the calling and called lines are connected, and ground is extended through the armature and front contact of relay 202, contacts of district selector switch 200, contacts 120 of group selector switch 450, contacts of final selector switch 400 to battery through the cut-off relay associated with the called line. The cut-off relay energizes in this 125 circuit and should the called line be in the process of extension through a line switch, the line relay is immediately released, thus preventing the called line being connected through the line switch with a sender selector and sender.

For the manner in which ringing current is applied to the called line and how disconnection takes place at the termination of conversation, reference is had to the Williams patent hereinbefore referred to.

What is claimed is:

1. In a telephone system, a plurality of lines, an automatic switch for extending said lines, means responsive to the initiation of a call on any one of said lines for preparing said automatic switch for operation, means effective upon the extension of said calling line for maintaining said automatic switch in operated condition, means for seizing said calling line as a called line, and means effective when said line has been so seized subsequent to initiation of a call thereon and while said line is in the process of being extended by said automatic switch for precluding further functioning of said automatic switch in the extending of said line.
2. In a telephone system, a plurality of lines, an automatic switch for extending said lines, means responsive to the initiation of a call on any one of said lines for preparing said automatic switch for operation, means effective upon the complete operation of said switch for maintaining the same in its operated condition independently of the calling line, means for seizing said calling line as a called line, and means effective when said line is so seized during the interval between the initiation of a call thereon and the complete operation of said automatic switch for arresting further operation of the latter in extending the said calling line.
3. In a telephone system, a line, an automatic switch for extending said line, means responsive to the initiation of a call on said line for preparing said automatic switch for operation, a second automatic switch, a recording mechanism, means effective upon the complete operation of said first switch for causing the connection of said second switch and said recording mechanism with said line, means under control of said recording mechanism for maintaining said first and said second automatic switches operated, and means effective when said line is seized as a called line subsequent to the initiation of a call thereon and prior to the extension thereof, for rendering said first automatic switch ineffective to connect with said second automatic switch and said recording mechanism.
4. In a telephone system, a line, an automatic switch for extending said line, a relay individual to said line, means for partially operating said automatic switch under control of said relay, a second automatic switch, a recording mechanism, means effective when said first switch is completely

operated for rendering it independent of said relay and for connecting said second switch and said recording mechanism to said line, means under control of said recording mechanism for maintaining said first switch completely operated, and means effective when said line is simultaneously initiating and terminating a call and prior to the complete operation of said first switch to render the latter ineffective to connect said line with said second switch and said recording mechanism.

5. In a telephone system, a calling line, an automatic switch for extending said line, means under control of the calling line for partially operating said switch, means for completely operating said switch, means effective upon the complete operation of said switch to render the latter independent of the calling line, and means effective when said line is functioning both as a calling and called line prior to the complete operation of the automatic switch to render said switch ineffective to extend said line as a calling line.

6. In a telephone system, a line, an automatic switch for extending said line, means responsive to the initiation of a call on said line for preparing said automatic switch for operation, means effective upon the complete operation of said switch for so maintaining the latter independent of the condition of said line, and means effective when said line is simultaneously initiating an outgoing call and terminating an incoming call prior to the complete operation of said switch for rendering the latter dependent upon the calling line.

7. In combination, lines, trunks, vertical rows of contacts in which said lines terminate, other vertical rows of contacts in which trunks terminate, link circuits for interconnecting said lines and trunks, a plurality of operating magnets each associated with a vertical row of contacts, a plurality of connecting magnets one for each of said link circuits, means responsive to the initiation of a call on one of said lines for preparing the operation of a plurality of said rows of contacts and operating one of said connecting magnets to extend said line, and means effective when said line is simultaneously initiating and terminating a call prior to the operation of said one of said connecting magnets to render the latter ineffective to extend said line.

8. In combination, a calling line, a plurality of outgoing trunks, a plurality of link circuits for interconnecting said line with an idle one of said trunks, a plurality of line magnets, a plurality of trunk magnets, a plurality of connecting magnets, means effective upon the successive operation of a line and a trunk magnet for preparing the operation of one of said con-

- necting magnets to extend the calling line, means effective upon the operation of said one of said connecting magnets to maintain the same in its operated condition independently of the calling line, and means effective when the calling line is simultaneously seized by a connector switch prior to the operation of said connecting magnet to cause the simultaneous release of said 10 switch and said connecting magnet.
9. In combination, calling lines, trunks, vertical rows of contacts in which said lines terminate, other vertical rows of contacts in which trunks terminate, link circuits for 15 interconnecting said lines and trunks, a plurality of operating magnets each individual to a row of contacts, a plurality of connecting magnets each individual to a link circuit, means for actuating a plurality of 20 said operating magnets for preparing the operation of one of said connecting magnets, an automatic switch, a recording mechanism, means effective upon the operation of said one of said connecting magnets for causing the association of said 25 automatic switch and said recording mech-

nism with a calling line, means under control of said recording mechanism for maintaining said connecting magnet operated, and means effective when said calling line 30 is simultaneously terminating an incoming call to render said connecting magnet ineffective to associate said calling line with said automatic switch and said recording mechanism. 35

10. In a telephone system, a plurality of lines, an automatic switch for extending said lines, means responsive to the initiation of a call on one of said lines for preparing said switch for operation, a second 40 automatic switch for seizing said line as a called line, and means effective when said second switch is about to seize said line while the same is in the process of being extended by said first switch for rendering 45 said first switch ineffective to extend said line and for allowing said line to be seized by said second switch.

In witness whereof, I hereunto subscribe my name this 5th day of February A. D. 1924.

EDGAR H. CLARK.
